UNITED STATES PATENT OFFICE.

JOHN D. WARRELL, OF DEWEYVILLE, TEXAS.

RAIL-TIE.

1,078,075.

Specification of Letters Patent.

Patented Nov. 11, 1913.

Application filed March 8, 1913. Serial No. 753,025.

To all whom it may concern:

Be it known that I, JOHN D. WARRELL, a citizen of the United States, residing at Deweyville, in the county of Newton and 5 State of Texas, have invented certain new and useful Improvements in Rail-Ties, of which the following is a specification, reference being had to the accompanying drawings.

10 This invention relates to improvements in rail ties, and more particularly to that class of ties which are made of metal.

An object of this invention is the provision of a tie to which the rails may be 15 quickly applied or removed, and one which will form a gage for the rails.

A further object of this invention is the provision of a rail tie which is hollow in construction, so that when the ties are laid 20 in low flat country where the track is subject to washouts, the water will pass through the tie rather than over it and minimize the danger of washouts.

A still further object of this invention is 25 the provision of a rail tie and fastening means by which the rails may be secured to the tie without the use of bolts or other devices which usually pass through the rails.

With these and other objects in view, my 30 invention consists in certain novel constructions, arrangements, and combinations of parts to be hereinafter more fully described, claimed and illustrated in the accompanying drawings, in which—

35 Figure 1 is a side elevation of my device; Fig. 2 is a top plan view thereof; Fig. 3 is a section on the line 3—3 of Fig. 2; Fig. 4 is a section on the line 4—4 of Fig. 2; Fig. 5 is a section on the line 5—5 of Fig. 2; Fig. 6 is a section on the line 6—6 of Fig. 2; Fig. 7 40 is a fragmentary top plan view partly in section; Fig. 8 is a perspective view of one of the locking plates which lock the wedge members in position; Fig. 9 is a section on the line 9—9 of Fig. 3; Fig. 10 is a perspective view of one of the braces which are used 45 to connect the meeting ends of a pair of rails, the rails being shown in dotted lines, and Fig. 11 is a perspective view of the other 50 brace used to connect the meeting ends of a pair of rails.

Referring more particularly to the drawing, the numeral 1 designates a hollow metallic tie, the upper wall 2 thereof being provided with openings 3 in its opposite ends, in

which suitable tools may be engaged to place the tie in position. The lower longitudinal edges of the tie are formed with outwardly extending flanges 4 to provide a greater tamping surface for the tie, the flanges being enlarged as at 5 near the opposite ends of the tie. The upper edges of the tie are provided with outwardly extending flanges 6 directly over the enlarged portions 5 of the flanges 4 and suitable braces 7 are disposed 60 between the flanges 5 and 6 to prevent bending of the upper flanges 6 when the rails 8 rest thereon.

It will be noted that the flanges 6 form an enlarged bearing surface for the rails, so 70 that if the ties are placed the usual distance apart, the distance between the rail bearing will be materially shortened thereby forming a more solid track and reducing the tendency of the rails to spread.

Formed in the top 2 of the rail are slots 9 which are arranged in pairs adjacent the opposite ends of the tie, the slots being formed with contracted portions 10 and enlarged portions 11, the enlarged portions of the slot extending inwardly of the tie. The rail clamps or braces 12 are arranged upon the top of the tie and are provided with a flat lower face to smoothly fit against the top wall of the rail, the clamps being formed 80 at their opposed ends with jaws 13 which are adapted to engage the base flanges of the rails. The clamps or braces 12 are provided with centrally depending T shaped lugs 14, the heads 15 of the lugs being adapted to 85 pass through the enlarged portions 11 of the slots and the shanks 16 of the lugs being of a size to engage in the contracted portions 10 so that the heads 15 of the lugs may engage under the top wall of the tie and maintain the clamps in slidable engagement therewith. It will be seen that the rails 8 are adapted to rest upon the portions 17 which separate the slots and transversely disposed on opposite sides of each pair of 90 slots are stop members 18 and 19 which are adapted to limit the movement of the rail clamps or braces. The outer stop members 18 are arranged a suitable distance from the ends of the slots, so that the jaws 13 of the outer stops will engage over the flanges of the rails, and the stop members 19 are arranged upon the tie at a slightly greater distance from the slots and the stop members 18 so that suitable wedge members 20 may 95

100

105

110

be interposed between the stop members 19 and the inner braces 12 so as to securely maintain the braces and rails in position.

The inner faces of the wedges 20 are 5 tapered and beveled as at 21 to engage the tapered and beveled outer faces of the stop members 19 to limit the inward movement of the wedges 20 between the stops 19 and the rail clamps 12 and also prevent vertical 10 movement of the wedges with relation to the tie. Tapered locking plates 22 are arranged on the top face of the tie between the clamps 12 and the stops 19, the plates being preferably formed of soft metal, 15 whereby the small ends 23 of the plates may be bent downwardly against the side face of the rail and the larger ends 24 of the plates may be bent upwardly against the larger ends of the wedges 20 to prevent accidental displacement of the wedge members.

In Fig. 3 of the drawings I have clearly 20 illustrated a form of fastening means for use in connection with the meeting ends of 25 a pair of rails, and in this connection the rails 8' are formed with openings 25 in the webs thereof, and one of the clamps 12' is formed with laterally extending studs 26, which are adapted to engage in the openings 25 in the meeting ends of the rail 8' to prevent the rails from separating longitudinally. The inner clamping member 12 is formed with a plurality of recesses 27 which are arranged in alignment with the 30 studs 26 and are adapted to receive the same to strengthen the connection between the clamps and the rails. The wedge members 20 are disposed between the ends of the inner faces 12' and the lugs 19 to maintain 35 the several parts in position. If desired, sound deadeners 28, which are composed of soft metal and are bent to conform to the shape of the jaws 13' of the clamps, are disposed between the jaws of the clamps and 40 the rails and are provided with openings 29 to receive the studs 26.

When it is desired to connect the rails 8 to a tie, which is constructed in accordance 45 with my invention, the enlarged heads 15 of the lugs 14 are disposed within the enlarged portions 11 of the slots, whereupon the clamps 12 are moved outwardly against the stops 18 and the rails are placed in position with the jaws 13 of the outer clamps 50 12 engaging the flanges thereof. The inner clamps 12 are then arranged upon the tie so that the jaws 13 thereof engage the opposite rail flanges whereupon the wedges 20

and locking plates 22 are disposed between the inner ends of the inner clamps and the 60 stop lugs 19 and the ends 23 of the locking members are bent downwardly against the side of the tie and the ends 24 of the locking members are bent upwardly against the wedges 20 and the device is then in position for use.

It will be seen that with this form of fastening devices, no bolts or other fastening means are disposed through the rail, the clamps 12 being maintained in frictional 70 engagement therewith by reason of the wedges 20 so as to prevent lateral movement of the rails and preventing them from spreading or turning.

A tie constructed in accordance with my 75 invention is self gaging, and will maintain the rails in the same relative distance apart for their entire length.

My metallic tie is formed preferably of 80 cast steel but may be formed, if desired, out of sheet metal which is bent to such shape as to form a hollow tie.

While the construction illustrated in the 85 accompanying drawings, is the preferred embodiment of my invention, it will be understood that minor changes in construction may be made without departing from the spirit of my invention or sacrificing any of its advantages as determined by the scope of the appended claim.

Having thus fully described my invention 90 what I claim as new and desire to secure by Letters Patent is:

The combination of a rail tie having longitudinal slots therein, rail holding clamps 95 having central depending lugs slidably disposed in said slots, said slots having enlarged portions at their inner ends, transversely extending stops arranged beyond the outer ends of said slots, one of said 100 clamps adapted to bear against one of said stops, a rail seated on said tie between said slots and engaging the last mentioned clamp, the other of said clamps being spaced from the other of said stops and bearing 105 against said rail, and a wedge member disposed between the last mentioned clamp and stop to maintain said clamps in engagement with the rail, as and for the purpose described.

In testimony whereof I hereunto affix my signature in the presence of two witnesses.

JOHN D. WARRELL.
